UNITED STATES PATENT OFFICE.

FRANK P. GALLIPOLI, OF NEW YORK, N. Y.

BLADE HONING AND SHARPENING DEVICE.

Application filed October 19, 1923. Serial No. 669,591.

To all whom it may concern:

Be it known that I, FRANK P. GALLIPOLI, a subject of the King of Italy, and a resident of the city of New York, borough of the Bronx, in the county of Bronx and State of New York, have invented a new and Improved Blade Honing and Sharpening Device, of which the following is a full, clear, and exact description.

10 This invention has relation to a device for honing and sharpening razor blades and aims as its principal object to provide an extremely simple, inexpensive and efficient device for this purpose.

15 As a further object the invention contemplates a device of the character set forth which greatly facilitates the operation of honing a razor blade and insures the proper positioning and guiding of the blade during 20 the honing operation.

With the above recited and other objects in view the invention resides in the novel construction set forth in the following specification, particularly pointed out in the appended claim and illustrated in the accompanying drawings, it being understood that the right is reserved to embodiments other than those actually illustrated herein to the full extent indicated by the general meaning 30 of the terms in which the claim is expressed.

In the drawings—

Figure 1 is a plan view of a device constructed in accordance with the invention, illustrating the use of the device for honing.

35 Fig. 2 is a sectional view therethrough taken approximately on the line 2—2 of Fig. 1.

Fig. 3 is a transverse sectional view taken approximately on the line 3—3 of Fig. 1.

40 Referring to the drawings by characters of reference, the device comprises a substantially U-shaped resilient or spring member 10 which is provided adjacent the free ends 11 and 12 with side flanges 13 which extend respectively above and below the ends 11 and 12 to define therebetween receiving spaces.

45 A pair of honing stones 14 are positioned between the confronting receiving spaces of the free ends 11 and 12, while a strap section 15 is positioned between the outer receiving space defined by the end 11 and its side flanges. The outer receiving space defined between the end 12 and its side flanges has positioned therein a canvas stropping section 50

55 16. Preferably the ends 11 and 12 are aper-

tured as at 17 and a suitable adhesive such as cement 18 is designed to secure the honing stones 14 and stropping sections 15 and 16 within the receiving spaces, the said adhesive or cement being adapted to extend through 60 the openings or apertures 17. The terminal of the free end 12 is offset as at 19 to overlie a portion of the forward end of the stone carried thereby and the extremity of said terminal forms a shelf 20 which is curved upwardly to form a rest and guide for the razor blade B or the supporting device S therefor in case a safety razor is being sharpened. Preferably the forward confronting faces of the stone sections 14 are beveled as at 21 70 whereby both sides of the cutting edge of the blade are simultaneously operated upon.

The inherent resiliency of the spring or resilient member 10 normally effects relative separation of the ends 11 and 12 as illustrated 75 in dotted lines in Fig. 2. In practice the blade is positioned to dispose its cutting edge between the stones 14 which are then brought into contact with the opposite sides of the cutting edge of the blade. The back of the razor or in case of safety razor blades, the support therefor, is then allowed to rest upon the shelf 20. By exerting a slight pressure to maintain the stones in contact with the blade, the honing may be readily accomplished by reciprocating the blade therebetween. When the honing operation is completed the blade is subsequently stropped on the canvas stropping strip 16 and finally finished on the strap section 15. 90

From the foregoing it will thus be seen that an extremely simple and inexpensive device has been provided by means of which the honing and sharpening of a razor blade may be effectually accomplished. 95

I claim:

A razor blade honing and sharpening device comprising a resilient U-shaped member defining relatively movable arms, a pair of honing stones secured respectively to the confronting faces of the free ends of the arms having beveled confronting faces at their forward ends, and a forwardly projecting and upwardly curved extension at the free end of one of the arms constituting a guiding and supporting means for the razor during the honing operation whereby to maintain the cutting edges in juxtaposition to the beveled faces. 100 105

FRANK P. GALLIPOLI.
